UNITED STATES PATENT OFFICE.

WILLIAM H. MANNS, OF WAYNESBORO, PENNSYLVANIA.

REFRIGERATING APPARATUS.

1,200,742.

Specification of Letters Patent. Patented Oct. 10, 1916.

Application filed November 16, 1909. Serial No. 528,410.

To all whom it may concern:

Be it known that I, WILLIAM H. MANNS, a citizen of the United States, residing at Waynesboro, in the county of Franklin and State of Pennsylvania, have invented certain new and useful Improvements in Refrigerating Apparatus, of which the following is a specification.

In the operation of ice making and refrigerating plants employing what is commonly known as the "flooded" system much difficulty has heretofore been experienced in securing satisfactory results on account of the periodical excessive generation of gas in the coils in the freezing tank caused by surplus heat resulting from the warming up of the brine from any occasional cause, such as the inserting of cans filled with warm water, the gas thus generated causing a back pressure in the coils and forcing the liquid backward, which, seeking an outlet of least resistance, passes up the liquid pipe leading from the ammonia supply pipe to the accumulator into said accumulator, causing the same to overflow onto the apparatus and run down the sides and adjacent parts, thus placing the apparatus in a bad condition and interfering materially with the process of freezing.

The object of my said invention is to provide certain improvements in the apparatus whereby these difficulties will be overcome and the disadvantage in the operation obviated, all as will be hereinafter more fully described and claimed.

Referring to the accompanying drawings which are made a part hereof and on which similar reference characters indicate similar parts, Figure 1 is a diagrammatical view of a refrigerating, or ice making, plant employing the "flooded" system, and Fig. 2 a detail view illustrating the construction of a check-valve forming a leading feature of the construction.

In said drawings the portions marked A represent the ammonia gas compressors, B the distilled water storage tank, C the freezing tank and D and E the accumulators. All of these parts are or may be of any approved construction and arrangement and need no special description.

The distilled water storage tank contains an ammonia liquid coil 5 connected with an inlet header 10 and an outlet header 11. The ammonia liquid supply pipe 12 is connected to the inlet header 10 and a suction pipe 13

to the outlet header 11. A system of pipe coils 6 for the ammonia liquid are also arranged in the freezing tank each connected to an inlet header 14 and an outlet header 15. A branch 16 leads from the ammonia liquid supply pipe 12 to the inlet header 14 and a suction pipe 17 leads from the outlet header 15 to the accumulator D. Another suction pipe 18 leads from the accumulator D and joins with the suction pipe 13 leading from the outlet header 11 of the distilled water tank, the two being connected by a coupling 19 containing a valve 20 by which the pipe 13 may be cut off from the pipe 18. A pipe 21 leads from coupling 19 into the accumulator D forming a part of the suction system. The main suction pipe 22 leads from the top of accumulator E to the ammonia gas compressors A, to which they are connected in the usual manner. A liquid return pipe 23 leads from the bottom of accumulator E and is connected by a coupling 24 with a branch 25 joined to the pipe 12 by a coupling 26. A frost indicator pipe 27 leads from the coupling 24 to near the top of accumulator E. A liquid return pipe 28 leads from the bottom of accumulator D to a coupling 29 and a branch 30 leads from said coupling into the branch 16 of the ammonia liquid supply pipe, being connected thereto by a coupling 31. A frost indicator pipe 32 leads from the coupling 29 to near the top of accumulator D. Various valves are provided in the various pipes for controlling the supply of liquid which are unnecessary to enumerate being plainly indicated in the drawing.

In the branch 30 between the ammonia liquid supply pipe 31 and the liquid return pipe 28, leading from the accumulator D, I have provided a check-valve 40, of any suitable construction, that shown in Fig. 2 being one that has been found desirable for the purpose. A similar check-valve 41 is provided in the branch 25 between the liquid return pipe 23, leading from the accumulator E, and the ammonia liquid supply pipe 12.

In operation, the accumulation of any gases caused by any sudden rising of the temperature of the brine surrounding the coils in the freezing tank will operate, as heretofore, to cause an excess gas generation, but the pressure will be in the direction of the outlet header, its back pressure being resisted and controlled by the check-valve 40 and prevented from forcing the liquid

through this channel into the accumulator. Such liquid as may be entrained with the gases through the header 15 and pipe 17 into the accumulator D will fall to the bottom of 5 said accumulator and be returned through pipes 28 and 30 into the ammonia liquid supply pipe 16 and back to the coils by gravity, while the gas will pass through the suction pipes, before described, to the ammonia gas 10 compressors.

The same operation will take place in the distilled water storage tank when for any cause the temperature of the water is raised to cause any unusual gas generation, the 15 globules of gas will be compelled to follow the course toward the outlet header into the suction pipe and to the gas compressors. By this means the circulation of the ammonia liquid through the system is placed absolutely 20 under control regardless of the variation in gas generation in the coils, caused by sudden changes in temperature and the operation of the apparatus can be maintained uniformly as desired, without the interference therewith and the difficulties heretofore experienced as above pointed out.

While I have described the invention as applied particularly to an ice making machine, it will be understood, of course, that 30 it is equally applicable to any refrigerating or cooling apparatus employing the "flooded system," such as "bunker" rooms, coils in cold storage rooms, etc.

Having thus fully described my said invention, what I claim as new and desire to 35 secure by Letters Patent, is:

1. In an ice making or refrigerating apparatus, the combination, of a water storage tank, liquid ammonia coils therein, a freezing tank, ammonia coils therein, an am-

monia supply pipe connected to the inlet head of each of said coils, an accumulator for each of said coils, an outlet pipe leading from one coil to one accumulator, another outlet pipe leading from the other coil into 45 the other accumulator, a gas outlet pipe leading from the accumulator of the freezing coil to the accumulator of the other coil, a suction pipe leading from said last named accumulator to the compressor, a separate 50 liquid return pipe, leading from each accumulator back to the liquid ammonia supply pipe, and a check-valve interposed in each of said return pipes between the liquid ammonia supply pipe and the accumulator 55 to prevent back flow of the liquid ammonia to the respective accumulators, substantially as set forth.

2. In an ice making or refrigerating apparatus, the combination of a water storage 60 tank, liquid ammonia coils therein, a freezing tank, ammonia coils therein, a liquid ammonia supply pipe connected to the inlet head of each of said coils, an accumulator, an outlet pipe leading from each of said coils 65 and connected with said accumulator, a liquid ammonia return pipe leading from said accumulator back to the liquid ammonia supply pipe, a back pressure check-valve interposed therein, and an exhaust pipe leading from said accumulator to a compressor, substantially as set forth.

In witness whereof, I, have hereunto set my hand and seal at Waynesboro, Pennsylvania, this 29th day of October, A. D. nineteen hundred and nine.

WILLIAM H. MANNS. [L. S.]

Witnesses:

EZRA FRICK,
A. D. FRICK.
